UNITED STATES PATENT OFFICE.

GUSTAV ADOLF BAUMANN, OF FORT MYERS, FLORIDA.

VISE.

SPECIFICATION forming part of Letters Patent No. 747,033, dated December 15, 1903.

Application filed March 12, 1903. Serial No. 147,488. (No model.)

To all whom it may concern:

Be it known that I, GUSTAV ADOLF BAUMANN, a citizen of the United States, residing at Fort Myers, in the county of Lee and State 5 of Florida, have invented new and useful Improvements in Vises, of which the following is a specification.

This invention relates to work-holding vises; and one of the objects thereof is to provide and construct a vise which will automatically clamp the work between the jaws thereof.

Another object is to dispense with the ordinary screw commonly used for adjusting 15 the two jaws and provide in lieu thereof means for removing the pressure against the movable jaw, so that the work can be removed in such a manner that both hands of the operator will be free to manipulate the 20 work.

Another object is to provide means for adjustably controlling the opposing jaws for work of different thicknesses.

Other objects as well as the novel details 25 of construction will be specifically set forth hereinafter, reference being had to the accompanying drawings, in which—

Figure 1 is a perspective view of a vise constructed in accordance with my invention, and Fig. 2 is a vertical longitudinal sectional view through the same.

In constructing the device an approximately rectangular skeleton frame is provided, which consists of the two end pieces 35 1 and 2, connected at their respective corners by the horizontal parallel supporting-bars 3, 4, 5, and 6. The lower longitudinal supporting-bars 3 and 4 are secured at the lower corners and on opposite sides of the 40 vertical end pieces 1 and 2 and are provided in their upper edges with notches or grooves 7, forming a rack and alining with similar notches or grooves 8 in the upper longitudinal bars 5 and 6, which are connected to the 45 upper opposite corners of the respective end pieces 1 and 2.

9 designates the rigid jaw, which consists of a vertical strip having its upper extremity curved in the form of a flange 10, disposed 50 at a right angle to the body portion of the jaw 9. This jaw 9 is rigidly fastened between the supporting-bars 3 and 4 and 5 and 6.

The movable or pivoted jaw 11 is secured to the bars 3 and 4 and adjacent to the lower extremity of the rigid jaw 9 and is provided 55 at its upper terminal with a flange 12, coinciding with the flange 10 of the jaw 9. The jaw 11 is approximately wedge-shaped—that is to say, the outer edge 13 of the jaw 11 is cut at an angle to the inner edge, so that the 60 outer surface diverges toward the upper terminal of the jaw. A standard 14 is arranged adjacent to the frame and bifurcated at its upper extremity to form arms 15 and 16, between which is journaled an elongated 65 bar 17, which extends transversely of the frame and one end of which projects therethrough between the upper and lower supporting-bars. Between the fulcrum-point 70 of the bar 17 and one extremity is an actuating-block 18, which is secured to the bar and is arranged adjacent to the diverging surface of the moving jaw 11. This block is to be moved vertically, so that the upward movement of the block will force the movable 75 jaw toward the rigid one and a downward movement will release it or permit it to move away therefrom, owing to the fact that the heavier portion of the jaw is at the upper extremity and to one side of the pivotal point 80 thereof. In order that the block 18 will be moved in a vertical direction, I provide an adjustable weight 19 at the opposite end of the bar 17, which engages one of the teeth of the rack 20, formed on the end thereof. The 85 forward or opposite end of the rod 17 can be depressed by a foot-piece or treadle 21, hinged to a block or support 22 and connected at its opposite end to the end of the rod 17 by a flexible connection 23.

The reference-numeral 24 designates a vertically-arranged strip having oppositely-disposed lugs or projections 25 near its top, which extend from the edges thereof and rest in the grooves 8. Similar lugs or projections 26 extend from the strip 24 near its lower end in opposite directions to engage the notches or grooves 7 in the lower supporting-bars 3 and 4. This strip constitutes a wall which is adjustable longitudinally of the frame and 90 through the medium thereof in connection with the moving block. The distance that will intervene between the edges of the opposing flanges 10 and 12 of the jaws 9 and 11 can be 95 100

governed. When the lugs of the wall 24 rest in the first set of notches, the upward movement of the block 18 will bring the opposing edges of the flanges 10 and 12 together, where-
 5 by a small article or piece of fabric can be se-
 curely clamped therebetween. As the wall
 is moved away from the jaws, however, the
 extreme limit of movement of the block 18
 will only be effective in moving the ends of
 10 the jaws toward each other, but not in con-
 tact. This will be desirable when it is nec-
 essary to clamp particles of various thicknesses
 between the jaws.

Of course it will be understood that the
 15 standard 14, the bar 17, the block 20, and
 their appurtenances can be moved toward
 either end of the frame to coincide with the
 position of the wall or strip 24. A suitable
 20 guide for this purpose can be arranged, if
 desired. Other changes can be made with-
 out essentially affecting the operation of the
 device—as, for instance, providing antifrictional
 25 rollers or balls in the head 18, whereby
 an easy movement on the block will take
 place between the wall 24 and the jaw 11.

This vise or work-holder can readily be set
 up, and owing to the peculiar arrangement
 of parts and the wide range of adjustment its
 adaptability to a multiplicity of uses will be
 30 readily appreciated.

I do not limit myself to the specific details
 of construction shown or the exact arrange-
 ment of parts, but I reserve the right to make
 such changes and alterations as would sug-
 35 gest themselves from time to time without
 departing from the spirit of this invention.

Having thus described my invention, what
 I claim, and desire to secure by Letters Pat-
 ent, is—

40 1. The combination with a rigid jaw and a
 movable jaw pivoted adjacent to the rigid jaw,
 of a vertically-moving block for forcing the
 pivoted jaw toward the rigid jaw, and an ad-
 justable wall against which the block slides
 45 to operate the pivoted jaw.

2. The combination with a rigid jaw and a

pivoted jaw, of an adjustable wall alining
 with the pivoted jaw, a fulcrumed bar inter-
 posed between the wall and the moving jaw,
 and means on the bar for moving the pivoted
 50 jaw toward the rigid jaw when the bar is ac-
 tuated.

3. In a device of the character described,
 the combination with a rigid jaw and a mov-
 able jaw, horizontal supporting-bars provided
 55 with grooves, a wall, means carried by the
 wall for engagement with the grooves, where-
 by the wall will be held in a vertical plane
 and in adjustable relation with the movable
 jaw, and means interposed between the wall
 60 and the movable jaw for actuating said jaw.

4. The combination with a rigid jaw and a
 pivoted jaw, one edge of the moving jaw be-
 ing arranged to diverge toward its free ex-
 tremity, a guide-wall vertically disposed, and
 55 a block interposed between the guide-wall
 and the diverging edge of the movable jaw
 for the purpose set forth.

5. The combination with a rigid jaw and a
 moving jaw, of an adjustable vertical guide-
 wall arranged in alinement with the rigid jaw
 and approximately parallel therewith, an ac-
 tuated lever and its support, said lever ex-
 70 tending between the wall and the moving jaw,
 the support and lever being adjustable with
 75 relation to the moving jaw, and an actuating-
 block carried by the lever to operate the mov-
 ing jaw.

6. The combination with a rigid jaw and a
 moving jaw, the moving jaw having one edge
 80 diverging from the other, of a vertical guide-
 wall alining with the rigid jaw and means in-
 terposed between the moving jaw and wall
 and adapted to slide therebetween whereby
 the moving jaw will be forced toward the rigid
 85 jaw.

In testimony whereof I affix my signature
 in presence of two witnesses.

GUSTAV ADOLF BAUMANN.
